UNITED STATES PATENT OFFICE.

JOSEPH J. TISCHLER AND WENDELIN A. TISCHLER, OF ST. PAUL, MINNESOTA.

DESIGN FOR A CHILD'S VEHICLE.

Application filed February 2, 1928. Serial No. 25,140. Term of patent 7 years.

To all whom it may concern:

Be it known that we, JOSEPH J. TISCHLER and WENDELIN A. TISCHLER, citizens of the United States, residing at St. Paul, in the county of Ramsey, and State of Minnesota, have invented a new, original, and ornamental Design for Child's Vehicle, of which the following is a specification, reference being had to the accompanying drawing, forming part thereof.

In the accompanying drawing:

The figure is a perspective view of a child's vehicle showing our new design.

We claim:

The ornamental design for a child's vehicle, as shown.

JOSEPH J. TISCHLER.
WENDELIN A. TISCHLER.
